United States Patent Office

Des. 182,096
Patented Feb. 11, 1958

182,096

PLATE OR SIMILAR ARTICLE

Shuzo Terano, Mizuho-ku, Nagoya, Japan, assignor to Noritake Co., Inc., New York, N. Y., a corporation of New York

Application September 20, 1957, Serial No. 47,800

Term of patent 7 years

(Cl. D44—15)

On the drawing,

The figure is a plan view of a plate or similar article,
showing my new design.

The plate is of a conventional configuration when viewed from the side and bottom thereof.

I claim:

The ornamental design for a plate or similar article,
substantially as shown and described.
